UNITED STATES PATENT OFFICE.

HENRY KOCH, OF HILTON, ILLINOIS, ASSIGNOR OF ONE-HALF TO B. F. SCHERTZ, OF SAME PLACE.

WAGON-TONGUE.

SPECIFICATION forming part of Letters Patent No. 274,342, dated March 20, 1883.

Application filed April 18, 1882. (No model.)

To all whom it may concern:

Be it known that I, HENRY KOCH, of Hilton, in the county of Tazewell, in the State of Illinois, have invented an Improved Wagon-Tongue; and I do hereby declare that the following is a full, clear, and exact description thereof, reference being had to the annexed drawing, making a part of this specification, in which like letters of reference refer to like parts, and in which the figure represents a plan of the same.

The object of this invention is the construction of a wagon-tongue which, when used with a three-horse whiffletree, shall permit the said triple-tree to be attached in the center line of the hounds of the wagon and said tongue still be midway between two of the horses. This construction entirely prevents any side draft to the team. When it is attempted to use three horses abreast in connection with an ordinary wagon-tongue, the center horse gets badly rubbed by the pressure of the tongue against his side. I have constructed my wagon-tongue in such a way that it rests midway between the center horse and right-hand one when used with an ordinary three-horse whiffletree, though it can, of course, be made as easily to go between the center and left-hand horses.

H' represents the forward axle-tree of a wagon, and *H H* the hounds.

The continuation *D* of the tongue *A* is bent off at an angle to form one side of the holding-frame *D B C*, being cut away at *N* to lessen the amount of bending and to carry said tongue *A* farther from the center line of the hounds *H*. By "center line of the hounds" I mean the line passing through the hounds perpen-

dicular to the axis *H'* at its center. The forward ends of the bars *B* and *C* of the holding-frame *D B C* are fastened together and to the tongue *A* by one or two bolts, *I*. The brace *E* presses apart the rear ends of the holding-frame bars *B C D* to fit the angle between the two beams *H H* of the wagon-hound. The center bar, *B*, serves simply to strengthen the holding-frame, and may be dispensed with by fitting a square block between the front part of the bar *C* and the tongue *A*.

I make two bolt-holes, *L L*, one at end of bar *B* and the other in *C*, to adapt the wagon-tongue for use with different makes of three-horse whiffletrees.

The wedge *G* serves two purposes: first, to prevent having to bend so far the end *D* of the tongue *A*, and, second, by moving it toward or from the end of the hound-bar *H*, to fit the wagon-tongue to different widths of hounds. When adjusted, a screw or two, aided by the bolt *F*, hold it in place.

The holding-frame of the tongue is pivoted to the hound by the bolt *F*, as in other constructions.

What I claim as my invention, and for which I desire Letters Patent, is as follows, to wit: The tongue *A*, cut away and bent at *N*, in combination with the bars *B C*, bolt *I*, brace *E*, and wedge *G*, substantially as and for the purpose specified.

In testimony that I claim the foregoing invention I have hereunto set my hand this 14th day of April, 1882.

HENRY KOCH.
